UNITED STATES PATENT OFFICE.

WILLIAM EDWARD GARFORTH, OF ALTOFTS, ENGLAND.

COAL-CUTTING MACHINE.

SPECIFICATION forming part of Letters Patent No. 613,987, dated November 8, 1898.

Application filed August 6, 1898. Serial No. 687,959. (No model.)

To all whom it may concern:

Be it known that I, WILLIAM EDWARD GARFORTH, a subject of the Queen of Great Britain and Ireland, residing at Altofts, in the county of York, England, have invented certain new and useful Improvements in Coal-Cutting Machines, (for which I have made application and filed provisional specification for Letters Patent in Great Britain and Ireland bearing date November 12, 1897, and numbered 26,394,) of which the following is a specification.

The object of my invention is to obviate or lessen the disadvantage which occurs with coal-cutting machines of the cutter-wheel type when working in highly-inclined seams with the working face to the rise side of the machine, in that the weight of the machine acting in the direction to the dip side tends to cause the machine and the cutter-wheel to gradually work away from the coal-face and to lessen the depth of the undercut.

I attain the object of my invention by means of a special construction of the bracket employed for carrying the center or journal of the cutter-wheel from one of the sides of the machine, which construction is illustrated in—

Figure 1 in plan and in Fig. 2 in section on line A B of Fig. 1, and Fig. 3 is a cross-section on line C D of Fig. 1 of the accompanying drawings, which form part of this specification. In Fig. 1 the bracket is shown broken away on one side, and in Fig. 2 a cross-section of the cutter-wheel rim is shown.

a indicates one of the side frames of the coal - cutting machine, to which side the cutter-wheel bracket is attached. The cutter-wheel bracket shown comprises these portions—to wit, an approximately triangular portion b, having the bearing c for the center or journal of the cutter-wheel formed in it toward the apex, and a vertical rectangular portion d, which abuts against the side frame a of the machine. Both these parts of the bracket run into each other with a curved portion f.

g is an opening formed in the curved portion f to admit the pinion engaging the teeth h of and driving the cutter-wheel i, and j is a smaller continuation of this opening to admit the shaft on which the aforesaid pinion is mounted.

Now my invention consists in forming the triangular portion b at such an inclination that while the machine is kept in a horizontal position—that is, with the side frame e vertical—the plane of the portion b of the bracket and that of the cutter-wheel are approximately parallel to the plane of the coal-seam. For example, the drawings show a bracket suitable for coal-cutting in a seam having an inclination of about twenty-five degrees.

Of course machines will be made with the parts b at various angles in order that such may be chosen for each coal-seam as will suit its prevailing dip. Mathematical exactness will not always be possible; but as a rule the approximation may be made sufficiently close without the need to tilt the machine.

In the case of other coal-cutters the bracket and cutter-wheel are approximately horizontal when the machine is horizontal, and consequently to cut in an inclined seam with such machines the machine itself must be tilted and one rail laid at a higher level than the other, so that the weight of the machine tends to draw the machine and cutter-wheel away from the coal-face, a tendency which is much assisted by the vibration of the machine itself when working. By forming the portion b of the bracket inclined to the portion d and making a proper selection of the machine with regard to the inclination of the coal-seam this tendency and the disadvantages arising therefrom are avoided.

In most machines the portions b and d of the bracket run into one another at a right angle, being strengthened or supported at the corner by ribs. I do not therefore limit my invention of inclining the triangular portion b to the vertical portion d to brackets such as I have above described and illustrated; but such brackets have the advantage that the machine can be laid closer to the coal-face and a greater depth of undercut obtained. Further, in the case of some wheel coal-cutting machines, especially such as are electrically driven, where the gearing does not project below the frame of the machine, the cutter-wheel bracket is formed with a horizontal portion passing beneath and by which it is attached to the frame of the machine, and I do not therefore limit my invention to

such cases as previously described, where the bracket is attached to the machine by a vertical portion; but

What I claim as new, and desire to secure 5 by Letters Patent, is—

1. In coal-cutting machines the combination of an approximately triangular plate *b* having about its apex the bearing for the center or journal of the cutter-wheel with a plate 10 *d* attached to the machine both formed in one piece and with the triangular plate or portion *b* inclined to the plate or portion *d* in order that when the machine is horizontal the inclination of the plate *b* may approximate that 15 of the coal-seam in which the machine is to be employed substantially as set forth.

2. In the cutter-wheel brackets of coal-cut-

ting machines the combination of a vertical portion *d*, an approximately triangular portion *b* having about its apex the bearing for 20 the center or journal of the cutter-wheel and a curved portion *f* having about its center an opening *g* all three portions being formed in one piece and with the portion *b* inclined to the portion *d* at an angle less than ninety degrees in order to approximate to the inclination or dip of the coal-seam in which the coal-cutting machine is to be employed substantially as set forth, for the purpose specified. 25

WILLIAM EDWARD GARFORTH.
